DESIGN FOR A HANDBAG OR SIMILAR ARTICLE

Jean Weisbard Meadow, New York, N. Y.

Application October 12, 1945, Serial No. 122,795

Term of patent 3½ years

(Cl. D87—3)

To all whom it may concern:

Be it known that I, Jean Weisbard Meadow, a citizen of the United States of America, residing in New York city, county of New York, and State of New York, have invented a new, original, and ornamental Design for a Handbag or Similar Article, of which the following is a specification, reference being had to the accompanying drawing, forming part thereof, wherein

The rear of the handbag or similar article, is substantially the same in appearance as the front.

I claim:

The ornamental design for a handbag or similar article, substantially as shown and described.

JEAN WEISBARD MEADOW.
